United States Patent Office

Des. 232,138

Patented July 23, 1974

232,138

OPHTHALMIC CHAIR

John Truman Armbruster, Niagara Falls, N.Y., assignor
to American Optical Corporation, Southbridge, Mass.

Filed Jan. 10, 1973, Ser. No. 322,349

Term of patent 14 years

Int. Cl. D6—01

U.S. Cl. D6—22

FIG. 1

FIG. 2

FIG. 3

Referring to the accompanying drawings:

FIG. 1 is a front perspective view of an ophthalmic chair embodying my new design;

FIG. 2 is a rear perspective view thereof; and

FIG. 3 is a perspective view of the ophthalmic chair as seen in a reclining position.

I claim:

The ornamental design for an ophthalmic chair, as shown and described.
